AGRICULTURAL IMPLEMENT CARRIER

George E. White, Winona, Kans., assignor to Johanna A. Michael, doing business as Michael Mfg. Co., Winona, Kans.

Filed Aug. 1, 1963, Ser. No. 76,070

Term of patent 14 years

(Cl. D14—3)

FIG. 1 is a perspective view of an agricultural implement carrier showing my new design;

FIG. 2 is a top plan view thereof on a reduced scale;

FIG. 3 is a side elevational view thereof;

FIG. 4 is a rear elevational view thereof on the same scale as FIG. 1; and

FIG. 5 is a front elevational view thereof.

I claim:

The ornamental design for an agricultural implement carrier, as shown.
